DESIGN FOR A COOKING-RANGE.

Design No. 12,925, dated May 9, 1882.

UNITED STATES PATENT OFFICE.

WILLIAM A. SPICER, OF PROVIDENCE, RHODE ISLAND.

DESIGN FOR A COOKING-RANGE.

SPECIFICATION forming part of Design No. 12,925, dated May 9, 1882.

Application filed March 20, 1882. Term of patent 7 years.

To all whom it may concern:

Be it known that I, WILLIAM A. SPICER, a citizen of the United States, residing at Providence, in the county of Providence and State of Rhode Island, have invented and produced a new and original Design for Cooking-Ranges, of which the following is a full, clear, and exact description, reference being had to the accompanying drawing, forming part of this specification.

The drawing is a photographic view of my newly-designed range, showing the peculiar features of the design.

Heretofore ranges have been variously ornamented to produce a pleasing effect; but in my present newly-invented design features original with myself, when applied to cooking-ranges, are used.

The leading features of my design consist, first, in the doors used in this cooking-range, consisting in a beveled surface, raised from the edge of the doors toward the center, ending in a border surrounding the panel, which is made with square corners at the bottom of the door and with rounded corners at the top of the door, the panel being sunk below the border at its edges and curved outward toward the center.

Another leading feature of my design consists in the ornamented bracket under the raised shelf, which consists in interlaced stems starting from the center and ending in scroll-work at the lower and upper ends. In the corners of these brackets open-work rosettes are inclosed in the scrolls, the whole forming a light open-work bracket having an extended base near the plate of the range, and projecting outward in the same manner under the shelf.

The upper part of the shelf is ornamented with a rail having a row of open-work rosettes with a larger rosette in the center surrounded by scroll-work.

The case rising from the plate of the range to the shelf has an ornamented panel in front and recessed rounded corners.

A A are the doors. b is the beveled surface, raised from the edge of the door. This surface is shown as ornamented with rectangular scrolls similar to what is known as a "Grecian

border;" but these ornamentations may be changed without materially altering the leading features of the design.

C is the raised panel of the doors, the surface of which curves into the recessed molding surrounding the panel.

d d are the ornamental brackets under the shelf, and e e the open-work rosettes.

f f are the rosettes forming the ornamental railing on the shelf B, and g is the larger central rosette surrounded by scroll-work.

h is the front panel of the case, rising from the range-top, D to the shelf B, and i i are the recessed rounded corners of the same.

K is the edge of the top and of the shelves, as also of the base of the range. The edges may be polished, and are made beveled with rounded corners, and the plate is raised above the rounded edge, representing in appearance a recessed rounded corner.

The beveled edge of the doors and the raised panels, with their upper rounded corners and recessed edges, form a very conspicuous part of the new design, while the open-work brackets under the shelf and the gallery or rail on top of the same give an individuality to the whole range which will be readily recognized, even when some of the details have been changed.

Having thus described my invention, I claim as new and desire to secure by Letters Patent—

1. The design in cooking-ranges herein shown and described, the same consisting in the doors of the same formed with the beveled surface b and the raised panel c, having square corners at the lower and rounded corners at the upper part of the panel, the panel being curved at its edges where it connects with the sunken molding surrounding the same.

2. The design in cooking-ranges herein shown and described, the same consisting in the ornamental brackets d d, placed under the shelf B, consisting of open scroll-work, carried outward at the bottom and top, having open-work rosettes e e in their corners.

3. The design in cooking-ranges herein shown and described, the same consisting in a rail or gallery, forming the back on top of

the shelf B, ornamented with the open-work rosettes *f f* and the central larger rosette, *g*, surrounded by scroll-work, as described.

4. The design in cooking-ranges herein shown and described, the same consisting in the doors A, ornamented as described, the edges K of the plates and shelves, the ornamental brackets *d d*, the case having the

rounded corners *i i*, and the ornamental railing on the shelf B, all combined as shown and described.

WILLIAM A. SPICER.
